UNITED STATES PATENT OFFICE.

JACOB F. GATES, OF PITTSBURG, PENNSYLVANIA.

HOLDER.

SPECIFICATION forming part of Letters Patent No. 587,724, dated August 10, 1897.

Application filed April 16, 1897. Serial No. 632,411. (No model.)

To all whom it may concern:

Be it known that I, JACOB F. GATES, a citizen of the United States of America, residing at Pittsburg, in the county of Allegheny and State of Pennsylvania, have invented certain new and useful Improvements in Holders, of which the following is a specification, reference being had therein to the accompanying drawings.

This invention relates to certain new and useful improvements in holders, and may be more particularly designated as a "curling-iron" holder, and is adapted to be attached to the top of a lamp-chimney, gas-jet globe, or the like, and receive the curling-irons while the same are being heated; and the invention aims to provide a holder of this class that will by its peculiar construction and arrangement hold the irons at the proper angle to heat the same in the portion desired and at the same time effectually prevent the heat of the flame from coming in contact with the handle of the irons, thus keeping the same cool at all times; and to this end the invention consists in the novel construction, combination, and arrangement of parts to be hereinafter more specifically described, and particularly pointed out in the claims, and in describing the invention in detail reference is had to the accompanying drawings, forming a part of this specification, and wherein like letters of reference indicate similar parts throughout the several views, in which—

Figure 1 is a perspective view of my improved curling-iron heater. Fig. 2 is a side view of the same, showing it applied to an ordinary lamp-chimney, which is shown in dotted lines. Fig. 3 is a similar view showing the application to a gas-jet globe.

To put my invention into practice, I form the holder *a*, which receives the curling-irons, and consisting of a tube, together with a shield *b* and the rear clamp *c*, of one piece of metal or other suitable material, the tube or holder being formed after the stamp has cut the sheet to the proper form. The rear holder *c* is formed by leaving intact with the shield *b* a strip *d*, having its end bent to form the clamp or holder *c*, which engages the lamp chimney or globe and supports the holder at the rear end, the front end of said

tube or holder being closed, and attached to this front or forward end is a rod *e*, which is bent V shape in form and swiveled in a keeper *f* on the holder or tube, the free ends of said rod having hook ends *g* *g*, which engage over the edge of the globe or chimney, and thus form a hanger to support the forward end of the holder. The shield *b* is provided around the edge that is in close proximity to the holder with a flange *b'*, which serves to deflect the heat and prevents same coming in contact with the handle. This hanger being longer than the support at the rear of the holder permits the forward end of the holder to incline downward toward the flame, and thus bring the forward end of the curling-irons into close proximity therewith, and by the arrangement of the shield the heat from the flame is prevented from coming into contact with the curling-iron handles, so that the same are retained cool and easily handled at all times.

I do not wish to be understood as limiting myself to the manner of forming the holder and the shield of one piece of metal or other suitable material, as this will of course depend somewhat upon the kind of material of which the holders may be manufactured, yet I have found this the cheapest and simplest mode of forming the same, and it will of course be further understood that the hangers may be made of any form desired to suit any particular globe or chimney and that other changes may be made in the details of construction without departing from the general spirit of my invention.

Having fully described my invention, what I claim as new, and desire to secure by Letters Patent, is—

1. In a holder of the class described, consisting of a tube, a clamp or holder, said tube and clamp or holder formed of a single piece of metal or other suitable material, a pivoted hanger secured to the tube, and adapted to engage the chimney or globe diametrically opposite to the clamp or holder, whereby said holder may be applied to chimneys or globes of different sizes, substantially as shown and described.

2. In a holder of the type described, a tube and shield, a clamp or holder for supporting the tube and shield at the rear, and a hanger

of greater length for supporting the tube at its forward end, substantially as shown and described.

3. In a holder of the type described, a tube having a closed and an open end, a shield formed integral with said tube, a holder formed integral with said shield, and a hanger attached at or near the forward end of the tube to support the same, substantially as shown and described.

4. A holder of the type described, consist-

ing of a tube, a shield and a holder formed of a single piece of metal or other suitable material, and a hanger attached to the tube for supporting the one end of the same, substantially as shown and described. 15

In testimony whereof I affix my signature in presence of two witnesses.

JACOB F. GATES.
